UNITED STATES PATENT OFFICE.

LOUIS JOHNSON AND GEORGE HOTTER, OF ST. PAUL, MINNESOTA.

BOTTLE-CARRYING HANDLE.

1,116,290.

Specification of Letters Patent.

Patented Nov. 3, 1914.

Application filed April 13, 1914. Serial No. 831,576.

To all whom it may concern:

Be it known that we, LOUIS JOHNSON and GEORGE HOTTER, citizens of the United States, residing at St. Paul, in the county of Ramsey and State of Minnesota, have invented certain new and useful Improvements in Bottle-Carrying Handles, of which the following is a specification.

Our invention relates to improvements in bottle carrying handles adapted particularly for use upon bottles or jugs having at the top an annular bead or flange, such as the milk bottles in common use, its object being to provide a carrying handle which cannot become detached from the bottle by the ordinary movements to which the bottle or handle is subjected in use, but which can be easily and quickly attached and detached by manipulation.

20 To this end the invention consists in the construction, combination, and arrangement of parts hereinafter described and claimed.

In the accompanying drawing showing an embodiment of the invention, Figure 1 is a perspective view of the improved bottle carrier shown in locked or clamping position; Fig. 2 is a side elevation of the carrier in place on a bottle neck, with the parts in locked or clamping position; and Fig. 3 is a 30 side elevation of the bottle carrier in unlocked or released position.

In the drawings the bottle carrying handle is shown applied to a bottle A, having at the top an annular flange or bead B. It 35 comprises two connected and interlocking members, made preferably of bent wire, namely, an attaching collar or clamp member 2 adapted to embrace the bottle neck and a carrier or bail member having a handle portion. The collar or clamp member is bent upon itself and twisted to form a closed 40 loop or eye 3 at about its middle point, and two outwardly and oppositely bowed semi-circular clamping arms adapted to fit about the neck of the bottle. These arms terminate, one in a loop or eye 4, and the other in an outwardly projecting latch 5.

The bail member is bent to form two upright arms 6 and 7 connected at the top by a handle portion 8 upon which is a hand piece 9. One of these arms, here designated as 6, is straight and formed at the bottom with a looped eye 10, which passes through the medial eye 3 of the attaching collar, while the 55 other arm, here designated as 7, is bent as

hereinafter described and formed at the bottom with an eye 11 which engages the terminal eye 4 upon one of the arms 2 of the collar member. The bent arm 7 of the bail member is formed with two bends, a rather 60 open bend 12 at about its middle point, and a deep and narrow bend 13 adjacent the loop 11. Both bends are projected in the same lateral direction, but the bend 13 is inclined downwardly in order to form a 65 holding catch for the latch 5 of the collar member.

In Fig. 1 of the drawings the parts of the bottle carrier are shown in locked position with the latch 5 of the clamping member lodged in the bend or catch 13 of the bail member. To arrange the parts for insertion over the flanged top of a bottle, the latch 5 is lifted with the finger and sprung up out of the bend or catch 13 so that it will lodge in 75 the middle bend 12 of the bail member 7. When the parts are in this position the clamping member will be tilted so that the arm which carries the latch will be considerably below the other arm.

To apply the device to the bottle the lower arm of the clamping member is inserted under the flange B of the bottle, as shown in Fig. 3 of the drawings. The handle is then bent backwardly to carry the upper arm of 85 the clamping member over the opposite side of the flange. When this has been done the parts will stand in the position shown in Fig. 3, except that the clamping arms will both lie around the neck of the bottle underneath the flange B. The latch 5 is then sprung down by the operator into the catch or bend 13 as shown in Fig. 2 of the drawings, thus clamping the collar members about the neck of the bottle underneath the 90 flange B. When the clamping members are thus locked about the neck of the bottle the latch cannot become dislodged by bending the bail backward or forward, nor by any ordinary movements to which the bottle or handle will be subjected in use. The clamping members can only be released by placing one finger under the latch and another finger upon the loop 4 and bending the handle backward. It will be observed that 105 the loop 3 upon the collar lies in a horizontal plane, while the loop 10 upon the bail member passes through it in a transverse plane, so that the loops will bind when the handle is bent over, and prevent the handle 110

from being bent over far enough in ordinary use to allow the latch to be disengaged unless opposite pressures are exerted upon the loop 4 and the latch 13, as above stated. It will be also observed that there is a shoulder 14 between the bends 12 and 13 in the bail arm 7 over which the latch must be sprung by the hand of the operator when it is moved from one bend to the other.

10 We claim as our invention:

1. A bottle carrying handle comprising a collar member and a bail member, the collar member having a medial eye and two oppositely out-bowed arms adapted to embrace the neck of the bottle, said arms terminating one in an eye and the other in a latch, and the bail member having two spaced arms pivotally secured to the medial and terminal eyes, respectively, of the collar member, the bail arm secured to said terminal eye being bent downwardly and laterally near said eye to form a catch loop for said latch, whereby to allow the latch to be moved into and out of locking engagement 25 with the catch loop without detachment of

either bail arm from the eyes of the collar member.

2. A bottle carrying handle comprising a collar member and a bail member, the collar member having a medial eye and two oppositely out-bowed arms adapted to embrace the neck of a bottle and terminating one in an eye and the other in a latch, and the bail member having two spaced arms pivotally secured to the respective eyes upon the collar member, one of said bail arms being formed with two lateral bends and an intermediate shoulder, the lower bend being positioned near the terminal eye upon the collar member and constituting a catch for said latch, said latch being capable of being sprung over said shoulder into one or other of said bends. 30 35

In testimony whereof we affix our signatures in presence of two witnesses.

LOUIS JOHNSON.
GEORGE HOTTER.
